UNITED STATES PATENT OFFICE.

JESSE C. KEEN, OF WHITEWOOD, VIRGINIA.

TOOL FOR WATCHMAKERS.

1,285,729.

Specification of Letters Patent.

Patented Nov. 26, 1918.

Application filed June 17, 1918. Serial No. 240,349.

To all whom it may concern:

Be it known that I, JESSE C. KEEN, a citizen of the United States, residing at Whitewood, in the county of Buchanan and State 5 of Virginia, have invented certain new and useful Improvements in Tools for Watchmakers, of which the following is a specification, reference being had to the accompanying drawings.

10 This invention relates to certain improvements in tools for watch makers and it is an object of the invention to provide a novel and improved tool which is particularly adapted for use in removing the hands from 15 a time piece.

The invention consists in the details of construction and in the combination and arrangement of the several parts of my improved tool whereby certain important advantages are attained and the device rendered simple, less expensive and otherwise more convenient and advantageous for use, as will be hereinafter more fully set forth.

20 The novel features of my invention will 25 hereinafter be definitely claimed.

In order that my invention may be the better understood I will now proceed to describe the same with reference to the accompanying drawings, wherein:

30 Figure 1 is a view in side elevation with a portion broken away of a tool constructed in accordance with an embodiment of my invention;

Fig. 2 is a sectional view taken substantially on the line 2—2 of Fig. 1; and

Fig. 3 is a sectional view taken substantially on the line 3—3 of Fig. 1.

As disclosed in the accompanying drawings 1 denotes an elongated shank or handle 40 having one end portion outwardly curved or bowed as indicated at 2 and secured to the side faces of the member or handle 1 at the opposite portions thereof are the spring plates 3. The outer or free extremities of 45 the plates 3 are provided with the inwardly directed flanges 4 for a purpose to be hereinafter more particularly referred to.

50 Threaded through one of the plates 3 and in swivel engagement with the second plate is an adjusting screw comprising a shank 5 having its outer end portion provided with a knurled head 6 whereby requisite rotation may be imparted to the shank 5 so that the outer or free portions of the plate 3 may be 55 adjusted one relative to the other.

At a predetermined point inwardly of the

plates 3 the member or shank 1 is provided with the transversely spaced pair of ears 7 extending in the same general direction as the plates 3. The ears 7 also overlie the side 60 faces of the straight lever 8 and disposed through the ears 7 and the lever 8 is a pin 9 whereby the lever 8 is mounted for rocking movement. Coacting with an end portion of the pin 9 and the adjacent ear 7 is a 65 clamping nut 10. The pin 9 is readily removed, after the nut 10 has been disengaged therefrom so that the lever 8 and the member or shank 1 may be separated when the occasions of practice so require and particularly when it is desired to cleanse the tool 70 or to remove rust therefrom.

The forward end portion of the lever 8 extends between the plates 3 and has its outer end substantially flush with the outer 75 end of the member or shank 1. Carried by the lever 8 at a point between the plates 3 and extending in the same general direction as said plates 3 is a pin 11 for a purpose which will be hereinafter set forth. 80

Secured to the inner face of the lever 8 rearwardly of its pivotal connection with the member or shank 1 is an end portion of a flat spring 12 and the opposite end portion of said spring 12 has sliding contact 85 with the inner face of the curved portion 2 of the member or shank 1. The spring 12 serves to normally maintain the opposed faces of the shank or member 1 and the lever 8 normally in contact so that the pin 11 90 is also normally housed between the plates 3 and thereby effectively protected against injury.

When it is desired to remove the hand from a time piece the shank 5 is rotated 95 in a direction to properly set the outer or free end portions of the plates 3. The tool is then manipulated to position the flanges 4 beneath the hands with the pin 11 substantially in alinement with the staff. Pull 100 is then imposed upon the rear portion of the lever 8 which results in the pin 11 contacting with the outer end of the staff which results in a movement of the plates 3 away from the staff. This latter movement of 105 the plates 3 causes the flanges 4 to force the hands from the staff and upon the pin 11.

From the foregoing description, it is thought to be obvious that a tool constructed in accordance with my invention is particularly well adapted for use by reason of the convenience and facility with which it 110

may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A tool of the class described comprising two relatively movable members, one of said members being provided with a pair of plates straddling the second member, the opposite end portions of the plates being provided with inwardly directed flanges, the second member being provided at a point between the plates with an outstanding pin extending in the same general direction as the plates.
2. A tool of the class described comprising two relatively movable members, one of said members being provided with a pair of plates straddling the second member, the opposite end portions of the plates being provided with inwardly directed flanges, the second member being provided at a point

between the plates with an outstanding pin extending in the same general direction as the plates, and means for adjusting the free end portions of the plates one relative to the other.

3. A tool of the class described comprising two relatively movable members, one of said members being provided with a pair of plates straddling the second member, the opposite end portions of the plates being provided with inwardly directed flanges, the second member being provided at a point

between the plates with an outstanding pin extending in the same general direction as the plates, the plates carried by the first named member being resilient, and a member having a shank in swivel engagement with one of the plates and threaded through the second plate whereby said plates may be relatively adjusted upon rotation of the shank.

In testimony whereof I hereunto affix my signature in the presence of two witnesses.

JESSE C. KEEN.

Witnesses:

G. W. COLE,
WILL HORN.
